US00D357742S

United States Patent [19]

Peery et al.

[11] Patent Number: Des. 357,742

[45] Date of Patent: ** Apr. 25, 1995

[54] **ELECTROTRANSPORT DRUG DELIVERY SYSTEM**

[75] Inventors: John R. Peery, Stanford; J. Richard Gyory, San Jose, both of Calif.

[73] Assignee: **ALZA Corporation**, Palo Alto, Calif.

[**] Term: 14 Years

[21] Appl. No.: 3,173

[22] Filed: Dec. 31, 1992

[52] U.S. Cl. D24/189

[58] Field of Search D24/189; 604/20, 19; 128/639

[57] **CLAIM**

The ornamental design for an electrotransport drug delivery system, as shown and described.

DESCRIPTION

FIG. 1 is a top perspective view of an electrotransport drug delivery system, showing our new design;

FIG. 2 is a top plan view thereof;

FIG. 3 is a bottom plan view thereof;

FIG. 4 is a side elevational view thereof taken along lines 4—4 of FIG. 2, the opposite side elevational view being identical to that shown; and,

FIG. 5 is a side elevational view thereof, taken along lines 5—5 in FIG. 2, the opposite side elevational view being identical to that shown.

FIG.1

FIG.2

FIG.3

FIG.4

FIG.5
